UNITED STATES PATENT OFFICE.

JOHN W. CALHOUN, OF CHESTER, PENNSYLVANIA.

METER BOX COVER.

1,421,669.

Specification of Letters Patent.

Patented July 4, 1922.

Original application filed March 20, 1919, Serial No. 283,713. Divided and this application filed May 28, 1921. Serial No. 473,516.

To all whom it may concern:

Be it known that I, JOHN W. CALHOUN, a citizen of the United States, and residing at Chester, in the county of Delaware and 5 State of Pennsylvania, have invented new and useful Improvements in Meter-Box Covers, of which the following is a specification.

This invention relates to meter box covers, 10 and particularly to a cover adapted and intended for use in conjunction with individual household water meters and in other like connections, the subject matter of 15 this case having been divided from application #283,713. An object of this invention is to provide a cover embodying two members adjustably fitted together whereby the cover is raised to the level of the surrounding earth or sidewalk, and which permits 20 readjustment and elevation of the cover without digging out and resetting the same in case the box settles.

Another object lies in providing inner and 25 outer covers or doors which have a dead air space therebetween.

A further object lies in arranging the inner cover so that for inspection and reading of the meter a small opening is provided, a door being fitted to this opening 30 and the entire inner cover being removable when access is to be had to the meter to detach or set the same.

With these and other objects in view, 35 which will be apparent from the drawing, specification and claims, this invention includes certain novel features of construction and combinations of parts which will now be set forth.

In the drawings:

40 Figure 1 is a vertical sectional view through my improved cover showing the same in place upon a meter box.

Fig. 2 is a horizontal sectional view taken on the line 2—2 of Fig. 1 and showing the 45 inner cover.

The upper and lower casing members 1 and 2, of cast iron or other suitable material, are of tubular form and have internal and external spiral flanges 3 and 4 50 adapted to mesh substantially as shown in Fig. 1.

The lower member 2 has a base flange 5 made of sufficient width to spread over the open top of a meter box 6 and rest on the 55 upper end thereof, the upper casing member

1 being in turn supported upon the lower member 2 by engagement of the spiral flanges 3 and 4. By turning the member 1 upon a vertical axis this member is raised or lowered, dependent upon the direction 60 in which it is turned, and adjustment is thus made to bring the open top member 1 to the level of the surrounding earth or sidewalk.

An internal supporting flange 7 is provided at the lower end of the casing member 2 as a support for the cover ring 8. This cover ring closes the major portion of the opening through casing member 2 to protect the meter installed within box 6, and 70 has an opening 9 through which the meter is visible for reading. A door 10 is pivoted or hinged at 11 at one side of opening 9 and is adapted to close down over this opening, handle or knob 12 being provided 75 for opening the door.

The outer casing member 1 has an internal supporting flange 13 adjacent its upper end with a hinge pintle 14 provided within a recess 15 at one side, and a bearing 80 portion 16 on a door 17 is received upon this hinge pintle to mount the door thereon. The door is adapted to swing down within the open top end of casing member 1 to rest upon bearing flange 85 13, and to retain the door in the closed position a locking member 18, and locking structure, similar to that shown in my co-pending application Serial Number 283,713 or of any other desired type, can be employed. 90

By constructing the inner cover as described above, and by providing the inner door, the meter or other instrument protected by my improved cover can be examined without the trouble and effort of removing the cover ring, although the entire inner cover may be removed when full access is to be had to the meter for removing or changing the same. By the arrangement 100 of inner and outer covers or doors, a dead air space is provided therebetween and the warmth of the earth and instrument is stopped and held in the box or housing, while cold air is prevented from entering. 105 Through the difference in temperature on the inner side of the inner door, due to leakage of air around the outer door, a film of frost or ice will form between ring 8 and flange 7, and the ring and door 10 so that the 110

inner cover is sealed, however when the door is to be opened or the entire inner cover removed, the thin film of ice or frost can be easily broken.

5 While, in the foregoing, I have described specific embodiments, and have mentioned only certain possible modifications, it will be appreciated that in practice I do not limit myself to such specific details as herein set forth, but may resort to any practical modifications falling within the scope of the invention as defined in the appended claims.

I claim:

15 1. A cover for meter boxes including upper and lower casing members having openings therethrough, a door for the opening of the upper casing member, a cover ring fitted within the opening of the lower casing member, and a door to close the opening of 20 said cover ring.

2. A cover for meter boxes and the like including with upper and lower casing members having openings therethrough and provided with flanges around said openings, a 25 cover ring removably supported on the flange of said lower casing, a door mounted on said cover ring to close the opening thereof, and a door mounted on said upper casing member to close against the flange thereof.

3. A cover for meter boxes and the like 30 including with upper and lower casing members each having an opening therethrough said lower casing member being provided with a supporting flange around the opening, a ring supported removably on said flange and through the opening of which ring access is had to the meter box, a door carried by said ring to close the opening thereof, and an outer door to close the opening of said outer casing member. 35

4. A cover for meter boxes and the like including with upper and lower casing members having openings therethrough and each provided with a supporting flange around said openings, a cover ring removably supported on the flange of said lower casing member to reduce the size of the opening thereof, a door hinged on said cover ring to close the opening thereof and to be opened to give access to the meter box, and an outer 45 door hinged on said upper casing member to shut against the flange thereof and form a second closure with an air space between the inner and outer door.

50 In testimony whereof, I affix my signature.

JOHN W. CALHOUN.
